UNITED STATES PATENT OFFICE.

SAMUEL MILLS BEVIN, OF EAST HAMPTON, CONNECTICUT.

DESIGN FOR A TOE-CLIP.

SPECIFICATION forming part of Design No. 25,913, dated August 11, 1896.

Application filed May 11, 1896. Serial No. 591,200. Term of patent 31 years.

To all whom it may concern:

Be it known that I, SAMUEL MILLS BEVIN, a citizen of the United States, residing at East Hampton, in the county of Middlesex and State of Connecticut, have invented and produced a new and original Design for a Toe-Clip, of which the following is a specification.

This invention relates to a design for toe-clips for bicycle-pedals.

10 The leading feature of the design is the representation of a toe-clip, substantially as hereinafter described.

This form of toe-clip embraces, among other advantages, those of general beauty and convenient form for fitting different shapes of shoe-tips or toes.

15 In the drawings accompanying and forming part of this specification, Figure 1 is a perspective view of a toe-clip, showing the design; and Fig. 2 is a top view thereof.

Similar characters designate like parts in both the figures of the drawings.

Referring to the accompanying drawings,

5 represents an elongated slotted portion, from the upper end of which extends a horizontal flat member, gradually widening to the front thereof, where it turns up in two relatively wide independent diverging semicircular backwardly and transversely concavo-convex arms 7 and 8, terminating at their upper ends in a slight upwardly-curved flat member 9, the outer lines of which gradually converge toward its free end, and which member runs substantially parallel to the member 6 and has an elongated opening 10 extending longitudinally thereof, the walls of which are in the nature of an ogee curve, and an opening 11 at its outer end in the nature of a star. 25

What I claim is— 30

The design for a toe-clip, substantially as herein shown and described. 35

S. MILLS BEVIN.
